UNITED STATES PATENT OFFICE

116,550

DESIGN FOR A CABINET FOR A MINIATURE BOWLING GAME

Edward J. Collins, Chicago, Ill., assignor to H. C. Evans & Co., Inc., Chicago, Ill., a corporation of Illinois

Application July 15, 1939, Serial No. 86,037

Term of patent 7 years

To all whom it may concern:

Be it known that I, Edward J. Collins, a citizen of the United States, and a resident of Chicago, in the county of Cook and State of Illinois, have invented a new, original, and ornamental Design for a Cabinet for a Miniature Bowling Game, of which the following is a specification, reference being had to the accompanying drawing, forming a part thereof, and in which:

Fig. 1 is a perspective view of a cabinet for a miniature bowling game embodying my new design; and

Fig. 2 is a rear elevational view thereof on a slightly larger scale, as seen from the direction indicated by the arrow 2 in Fig. 1.

I claim:

The ornamental design for a cabinet for a miniature bowling game, as shown.

EDWARD J. COLLINS.
